David N. Carlson and Adrian E. Huskins,
Burbank, Calif.

Application May 10, 1948, Serial No. 146,256

Term of patent 14 years

(Cl. D37—1)

To all whom it may concern:

Be it known that we, David N. Carlson and Adrian E. Huskins, citizens of the United States, residing at Burbank, in the county of Los Angeles and State of California, have invented a new, original, and ornamental Design for a Knife Sharpener or the like, of which the following is a specification, reference being had to the accompanying drawing, forming part thereof.

In the drawing:

Fig. 1 is a perspective view of the knife sharpener or the like, showing our new design;

Fig. 2 is an elevation in the direction of the arrow 2 of Fig. 1.

We claim:

The ornamental design for a knife sharpener or the like, as shown.

DAVID N. CARLSON.
ADRIAN E. HUSKINS.
